UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF CANADA.

MANIFOLDING SALES-BOOK.

1,107,578.

Specification of Letters Patent. Patented Aug. 18, 1914.

Application filed July 3, 1912. Serial No. 707,422.

To all whom it may concern:

Be it known that I, EDWARD KIRBY BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

This invention relates to manifolding sales books and with regard to certain more specific features thereof, to triplicate sales books.

One of the objects of the present invention is to provide a simple and practical sales book of the above character.

Another object is to provide a sales book which shall be easy to manipulate and cheap to manufacture.

A further object is to provide a sales book particularly adapted for use in clubs and the like, and constructed to prevent fraud.

Other objects will be in part obvious and in part pointed out hereinafter.

The invention accordingly consists in the features of construction, combinations of elements and arrangement of parts which will be exemplified in the construction herein-after set forth, and the scope of the application of which will be indicated in the following claims.

In the accompanying drawing, wherein is shown one of the various possible embodiments of this invention, Figure 1 is a perspective view of the complete device in operative position, with certain parts broken away for the sake of clearness; and Fig. 2 is a side elevation of a slightly modified form. Similar reference characters refer to similar parts throughout both views of the drawing.

Referring now in detail to the accompanying drawing, but more particularly to Fig. 1, 1 denotes the rear cover of a holder having flexibly connected therewith by means of a hinge 2 a top cover 3. At the opposite end the bottom cover 1 is flexibly connected, by means of a hinge 4, a back 5. Both the bottom cover and back are provided with pockets 6 and 7 respectively adapted to receive pads. One of these pads 8 comprises a plu-

rality of sets of original and duplicate leaves 9 and 10 respectively, connected at their lower or free ends and provided with a line of perforations 11 whereby they may be conveniently separated. The leaves are also bound together at their upper ends by means of staples 12 to form a stub 13 separated by weakening lines of perforations 14 to permit the leaves to be readily detached. The back of each original leaf 9 is carbonized or coated with manifolding material as indicated at 15 by the torn portion whereby a record is made upon the duplicate leaf 65 immediately therebeneath. It is seen that each set of leaves is connected at both ends so that erasures or changes upon the duplicate leaf can not be made without being easily detected, as it will necessitate the separating of the leaves at either their top or bottom. The other pad 16, hereinafter referred to as the triplicate pad, comprises a plurality of single leaves 17 bound together by means of staples 18 to form a stub 19. 70 These leaves are also provided with perforations 20 whereby they may be easily and quickly detached. Bound with the leaves of the triplicate pad is a carbon or manifolding sheet 21, and normally resting thereover. It is thus seen that when an impression is made upon the original leaf 9 it will be duplicated upon the leaf 10 by means of the manifolding means 15 and triplicated upon the leaf 17 by means of the carbon sheet 21. 85

Having described the construction of one embodiment of the invention, the operation thereof is substantially as follows: In clubs, where a book of this character is particularly desirable, and where members of the clubs sign checks for articles received, it is customary for the club at the end of the month to render a statement of the member's account and also return the checks signed. By the use of a triplicate book of this kind, 95 one set may be retained at the club, a second set returned to the member at the end of the month, while the third set takes its regular course to the kitchen or other department supplying the goods ordered. Thus when 100 the guest is waited upon his order is taken and recorded upon the original sheet 9 and duplicated and triplicated in the manner above described, after which the three leaves

are detached and disposed of as necessary. The triplicate pad is then swung upwardly from the plane of the original pad, a second set of original and duplicate leaves is turned back from the pad 8 from its position normally beneath the triplicate pad and laid over the triplicate pad after the latter is returned to its normal position. The book is then ready for subsequent operations.

10 In Fig. 2 the construction is substantially the same except that the original leaf 9 of the pad 8 is not bound at the stub with the duplicate leaves but terminates at the line of perforations 14. The operation thereof is, of course, substantially the same as that above described. It is thus seen that this invention provides a simple and practical device adapted to accomplish, among others, all of the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

20 Having described my invention, what I claim as new and desire to secure by Letters Patent is:

1. In a manifolding salesbook, in combination, a holder, a back, a pad comprising a plurality of original and duplicate leaves mounted upon one of said parts, a second pad of triplicate leaves mounted upon the other and operatively associated with said first-mentioned pad and manifolding means 25 associated with each of said pads whereby triplicate copies may be made when the parts are in operative position.

2. In a manifolding sales book of the character described, in combination, a pad comprising a plurality of sets of original and duplicate leaves, the leaves of each set being connected at both ends, and a triplicate pad connected with said first-mentioned pad to rest beneath the top set of original and 30 duplicate leaves.

3. In a manifolding sales book of the character described, in combination, a pad comprising a plurality of sets of original and duplicate leaves, the leaves of each set being connected at both ends, a triplicate pad connected with said first-mentioned pad to rest beneath the top set of original and 35 duplicate leaves, and manifolding means contacting with both sides of the duplicate leaf.

4. In a manifolding sales book of the character described, in combination, a pad comprising a plurality of sets of original and duplicate leaves, the leaves of each set being connected at both ends, a triplicate pad

connected with said first-mentioned pad to rest beneath the top set of original and duplicate leaves, a manifolding medium applied directly to the back of the original leaf, and a carbon sheet connected with the triplicate pad.

5. In a manifolding sales book of the character described, in combination, a pad comprising a plurality of sets of original and duplicate leaves, the leaves of each set being connected at both ends, a triplicate pad connected with said first-mentioned pad to rest beneath the top set of original and duplicate leaves, manifolding means applied directly to the back of the original leaf, and manifolding means beneath the duplicate leaf.

6. In a manifolding sales book of the character described, in combination, a pad comprising a plurality of sets of original and duplicate leaves, said leaves being connected at both ends, manifolding means applied to the back of each original leaf, a triplicate pad connected with said first-mentioned pad normally positioned beneath the top set of leaves, and a manifolding sheet connected with said triplicate pad.

7. In a manifolding sales book of the character described, in combination, a holder having a back hinged along one edge thereof, a pad comprising a plurality of sets of original and duplicate leaves removably mounted upon said holder, the original and duplicate leaves of each set being connected at their unbound ends, a triplicate pad comprising a plurality of single leaves bound together along one edge removably mounted upon said back and operatively positioned with relation to the top set of original and duplicate leaves, and manifolding media located both above and below said duplicate leaf whereby transactions are recorded in triplicate.

8. In a manifolding sales book of the character described, in combination, a holder having a back hinged along one edge thereof, a pad comprising a plurality of sets of original and duplicate leaves removably mounted upon said holder, the original and duplicate leaves of each set being connected at both ends, a triplicate pad comprising a plurality of single leaves bound together along one edge removably mounted upon said back and operatively positioned with relation to the top set of original and duplicate leaves, and manifolding media located both above and below said duplicate leaf whereby transactions are recorded in triplicate.

9. In a manifolding sales book of the character described, in combination, a holder having a back hinged along one edge thereof, a pad comprising a plurality of sets of original and duplicate leaves mounted upon said holder, the original and duplicate leaves of

each set being connected at thin unbound ends, a triplicate pad comprising a plurality of single leaves bound together along one edge mounted upon said back and operatively positioned with relation to the top set of original and duplicate leaves, manifolding means applied directly to the back of the original leaf, and a manifolding sheet con-

nected with said triplicate pad positioned beneath the duplicate leaf. 10

In testimony whereof I affix my signature, in the presence of two witnesses.

EDWARD KIRBY BOTTLE.
